 J. Wm. Best

United States Patent Office.

JOHN BEST, OF LANCASTER, PENNSYLVANIA.

Letter's Patent No. 60,990, dated January 8, 1867.

FURNACE FOR STEAM BOILERS.

The Schedule referred to in these Letters Patent and making part of the same.

TO ALL WHOM IT MAY CONCERN:

Be it known that I, JOHN BEST, of Lancaster, in the county of Lancaster, and State of Pennsylvania, have invented a new and useful improvement on Steam Boilers; and I do hereby declare that the following is a full and exact description of the construction and operation of the same, reference being had to the accompanying drawings, making a part of this specification, in which—

Figure 1 is a perspective view of my boiler, showing the front and side, with the doors D of the gas-chamber C open, to show the tubular flues, as also the doors G of the fire-box, to show the grate.

Figure 2, a perspective outline or descriptive view of the same, showing the rear partition I J, or chamber around the vent or smoke pipe K, and rear of the boiler, &c.

Figure 3 is a horizontal section to show the manner of connecting the gas-chamber with the boiler in front; also the partitioned or walled chambers M L, in the rear of the boiler and walls of the furnace A.

Figure 4 is a front elevation of the same.

The nature of my invention consists in providing a gas-burner or chamber over the furnace or fire-box, in front of the boiler, so connected with the boiler that a new chamber can be put on when burned out, without otherwise affecting the boiler, and by preventing the escape of the heat into the stack by a check-wall, so as to drive the heat, when it has passed under the surface of the boiler, to one side, as it rises, and drawing it forward through the tubular flues on the water level, into the gas-chamber, where the gaseous product of combustion is ignited, augmenting the heat, and carried through the tubular flues on the other side of the central partition in the boiler, (also on the water level,) back into the vent-chamber, from whence it escapes into the stack, thereby increasing both the heat and draught and greatly economizing fuel, it being thoroughly utilized in causing the heat to circulate on the water level through the gas-consuming chamber, which has now been tested as a fact, no longer resting upon theory, which is equally well established in the consumption of the gaseous products.

To enable others skilled in the art to make and use my invention, I will proceed to describe its construction and operation.

I construct my boiler on the ordinary plan of steam boilers, allowing the front plates of its circumference to project beyond the head a few inches, the flange around the head being turned inwards under the outer cylinder forming the boiler. To this projecting rim of the same I attach the portion constituting the chamber C, say about the one-eighth or one-ninth of the entire length of the boiler proper, in depth, (this may vary with the length and diameter of boilers, however,) this being properly secured over and to the same, and closed in front by partial heading, N O, fig. 4, connected centrally by a stout iron rod or fixture, to which the doors D are hinged to close the intermediate space between the partial heading N O of the gas-chamber C, which thus comes in front of and is open to the head and flues E' E'' in the boiler, and directly over the anterior portion of the fire-box F in the furnace A. The flues E' E'' are divided by a vertical partition, P, in two separate series, from each other. The furnace-flue L admits the heat from the fire-box F to pass under the boiler to the water level in its rear, where it is deflected to one side, say into chamber M, by a wall or partition, I J, shutting it off from the flue K, and thus made to pass through the flues E' on one side of the vertical partition P, through its series to the water level, entering the gas-chamber C heated to redness by the fire directly under it, igniting the gaseous products which would otherwise escape with the smoke into the stack, and thus the utility of its combustion, as so much additional fuel, lost; but by these means the combustion is secured and the heat greatly augmented, with a consequent increase of draught. It is again carried on the water level through the series of flues E'' on the other side of the vertical partition P, back to the rear of the boiler, into the chamber I surrounding the flue K, that conveys it into the stack. The novelty and utility consist in the mode of conducting the heat and consuming the gaseous products of the fuel, and while it utilizes all the fuel, the heat is more judiciously applied on both sides to the water level within the flues.

I am aware that tubular boilers are in use in which the heat is carried back under the boiler to the water level, but it is returned, either through the lower series of flues and passes back through the upper, or first through the upper series, and then on the drop-flue principle carried back through the lower series divided horizontally, while I divide mine vertically and carry the heat both ways on the same plane and water

level through the flues, both forward and back again, by which arrangement itself I have an increased benefit, independently of the further combustion and increase of heat obtained by the use of my gas-burning chamber C, thereby, jointly, greatly increase the efficacy of the heat, as well as a great saving in the consumption of fuel to generate the same amount of steam.

I claim the prolongation of the outer cylinder B of the boiler beyond the flues, when closed with a partial head, N O, and doors D D, so as to form a chamber, C, directly over the front part of the furnace or fire-box F, constructed in the manner and for the purpose specified.

I also claim the vertical partition P, in boilers, in combination with a partition or chamber, I M, for conveying the heat first under, then through, a series of flues E', on one side, on the water level, and returning it on the same plane, on the other side of said partition P, through the flues E'' to the rear of the boiler, substantially in the manner specified.

JOHN BEST.
